GRINDING PLATE

David S. Anthony, San Antonio, Tex.

Application January 13, 1936, Serial No. 58,815

3 Claims. (Cl. 83—3)

This invention relates to new and useful improvements in grinding plates.

One object of the invention is to provide improved complementary grinding plates particularly adapted for use in grinding material which is fed to the plates from the center thereof and is ejected from the periphery of said plates, the plates being constructed so as to more efficiently perform the grinding operation.

10 An important object of the invention is to provide an annular grinding plate having portions along its inner edge bent out of alignment with the plane of the plate, whereby, when two plates are placed cooperatively together, the bent portions will provide enlarged inlets for the material to be crushed between the plates, whereby a uniform feed and decortication, granulation or pulverization of the material is had.

Another object of the invention is to provide 20 an improved grinding disk having concentric rows of sharpened protuberances such as burrs, serrations or teeth on its working face extending from its inner edge to near its outer marginal portion, said burrs, serrations or teeth being all 25 of the same depth and pitch; and additional rows of smaller burrs, serrations or teeth on said outer marginal portion all being of the same pitch, the protuberances on said outer marginal portion being approximately only one-half the size of the 30 other protuberances, whereby the finer or smaller ones serve to finish the grinding operation, which increases the working capacity of the mill and improves the quality of the product.

35 A further object of the invention is to provide an improved grinding plate which includes a base member and a supplemental disk arranged to be secured thereto, the disk having the grinding teeth made thereon, whereby, when the teeth become dull and replacement is necessary, said 40 disk may be removed from the base member and a new disk substituted therefor, instead of replacing the entire grinding element; also, this structure permits making the supplemental grinding disk of thin steel, whereby the teeth 45 formed thereon may be made sufficiently sharp for fine grinding, thereby attaining all the advantages of a steel disk without the increased cost incidental to constructing a thick integral steel plate.

50 A construction designed to carry out the invention will be hereinafter described, together with other features of the invention.

The invention will be more readily understood from a reading of the following specification and 55 by reference to the accompanying drawing, in

which an example of the invention is shown, and wherein:

Figure 1 is a face view of a supplemental grinding disk or plate constructed in accordance with the invention.

Figure 2 is a transverse, sectional view of the same, taken on the line 2—2 of Figure 1.

Figure 3 is a cross-sectional view taken on the line 3—3 of Figure 1, on an enlarged scale.

Figure 4 is a sectional view, showing two cooperatively opposed complementary grinding plates in working registration.

Figure 5 is a face view of the base member or supporting body plate, and

Figure 6 is a transverse, sectional view, taken on the line 6—6 of Figure 5.

In the drawing, the numeral 10 designates a circular flat disk which is preferably made of steel, but which may be constructed of any suitable material. The disk is formed with an axial 20 opening 11 which extends therethrough. The disk as shown is comparatively thin but may be of any desired thickness.

A multiplicity of enlarged grinding burrs, or teeth 12, formed on the working face of the disk 25 are arranged in concentric rows which extend from the inner edge thereof at the axial opening 11 to an annular line 13 near the marginal portion of the disk. The teeth are preferably V-shaped in cross-section or pyramidal in form and 30 the pitch of all of the teeth of said group is constant whereby the majority of said teeth are all of the same size.

Any suitable method may be employed in forming the teeth. However, it has been found 35 desirable to form said teeth by first cutting concentric V-shaped grooves 11' of the proper depth in the face of the disk. After these grooves have been cut, the disk is placed in a planer or milling machine, and V-shaped channels or cuts 12' 40 which cross the concentric grooves are milled. The cross cuts do not extend radially from the center of the disk but are formed in groups B, the cuts of each group being parallel. The first 45 cut C of each group extends tangentially from an imaginary circle A, shown in dotted lines, which has a diameter smaller than the diameter of the axial opening 11. Thus, it is obvious that the concentric grooves and cross-cuts form pyramidal burrs or teeth 12 on the face of the disk. 50

Extending from the annular line 13 on the periphery of the disk to the edge thereof, an annular outer group of grinding burrs or teeth 14 are provided. The teeth 14 are also arranged in concentric rows, are V-shaped in cross-sec- 55

tion, and are formed in the same way as the teeth 12. However, the teeth of this annular outer group, as is clearly shown in Figures 1 and 4, are smaller than those of the groups of 5 teeth 12, preferably being substantially one-half the size thereof. It is noted that the pitch of the teeth 14 is constant, whereby all of said teeth 14 are of the same size.

From the above, it will be seen that a circular 10 grinding disk having two distinct sets of grinding teeth is provided; a multiplicity of enlarged teeth 12 which covers the major portion of the face of the disk, and a group of comparatively fine or smaller teeth which are located annularly at the marginal portion of the disk.

After the teeth or burrs 12 and 14 have been 15 formed on the disk face, said disk is again placed in a milling machine and a plurality of slots 15 are cut therein. The slots extend tangentially 20 from the imaginary circle A, and cut entirely through the disk. As is clearly shown in Figure 1, said slots extend from the inner edge of the disk at the axial opening 11 to a point beyond the middle of the groups B of enlarged burrs or 25 teeth 12. It is obvious that the cutting of the slots divides the inner portion of the disk into a plurality of sections D. These sections are then bent so that their inner edges are out of alignment with the plane of the disk. It is noted that 30 as shown the sections are bent at one corner away from the face of the disk so that if the disk were lying horizontal with its teeth uppermost, the sections D are bent downwardly. When so bent, the inner portion of the disk is 35 provided with a plurality of corner curved wings. After the plate is so formed, it is, of course, properly tempered and hardened.

In completing the grinding plate, a circular base or supporting body member 16 having an 40 axial opening 16' is provided. This member has an upstanding peripheral flange 17 and an annular internal shoulder 18 just below said flange. The shoulder is comparatively narrow in width 45 and between the inner periphery of the shoulder and the inner edge of the base member, said member is formed with sector-like recesses 19 the bottoms of which are curved so as to correspond to the curved wings of the disk 10.

The disk 10 is placed within the supporting 50 member 16 so that the underside of its annular outer marginal portion rests on the internal shoulder 18 with the peripheral flange 17 encircling the edge of said disk 10. The curved wings of the disk 10 engage in the curved recesses 19 of the supporting body member 16, and the axial opening 11 in said disk 10 registers with the opening 16' in the member 16. The disk 10 is provided with a plurality of bolt holes 20 which register with threaded openings 21 in the member 16, when said disk is located on said member 16. The bolt holes are countersunk so as to receive 60 the heads of machine screws (not shown) which pass through the disk and are screwed into the openings 21 of the member 16 to securely fasten 65 the disk and member together to form the complete grinding plate.

In actual use, two cooperatively opposed plates are provided and are positioned face to face so 70 that the concentric rows of teeth on one plate enter between the rows of teeth on the other plate. When so positioned, the opposed curved wing portions of each disk flare away from each other, whereby the teeth of said curved wing portions do not enter between each other.

75 The material to be ground is supplied through

the registered axial openings 11 and 16' in the usual way and as one cooperatively opposed plate rotates with relation to the other, the material enters between the curved or flared wing portions and is fed from between the wings to between 5 the inter-projected teeth 12 and 14 on the non-slotted annular outer portions of the complementary disks. Due to the curvature or flare of the wings, it will be seen that an enlarged inlet space is provided, which eliminates all danger 10 of crowding the feed, whereby a smooth and even feed is had.

After the material is introduced between the plates, the group of enlarged teeth 12, which are all of the same size, serve to crush and grind the 15 material. If grain is being ground, the same is hulled by these larger teeth. Since the teeth are all of the same size it is obvious that so long as the grain is passing therebetween, the grinding action is smooth and even, as there is no 20 choking effect due to a reduction in the size of the teeth.

By the time the material reaches the marginal portion of the disk, where the annular group of smaller teeth 14 is located, it is well ground, and 25 since all the heavy work has been done, this group of smaller teeth merely finishes the work to further grind and reduce or pulverize the material. Since the groups of teeth 14 are all of the same size, there is no retarding or choking of the material passing therebetween just prior to ejection 30 due to a gradual increase in the number of the grinding teeth from the central inlet towards the peripheral outlet.

Thus, it is seen that each disk has the two 35 groups of teeth, the major inner one with larger teeth all of the same size, and the outer one with smaller teeth all of the same size. The inner portion of each disk, as hereinbefore described, may be flared or curved, so as to provide an increased inlet, but, in some cases, only one of the cooperatively opposed disks may have its wing portions flared, the wing portions of the complementary disk being straight, as shown in Figure 4 of the drawing. It is noted that these initial 45 material-receiving wings have some of the teeth 12 thereon and these teeth aid in feeding the material to the major working space between the disks.

It is pointed out that since the disk 10 is made 50 of thin steel, the advantages appurtenant to steel cutting teeth are had, while the expense of making the entire thickness of the plate of steel is overcome. Also, the teeth are formed on the disk and then said disk is tempered. It is well 55 known that during the tempering operation, the thin disk may warp slightly but by bolting the disk to the base member 16, the disk is straightened out when the bolts are tightened, after the forming of the teeth and tempering, and at the 60 same time said disk is rigidly fastened in proper position on the body member 16.

It is noted that when the burrs or teeth of the disks become dull it is only necessary to remove the disks 10 from the supporting members 16 and 65 substitute new disks therefor. It being unnecessary to replace the entire device, the operating and maintenance cost is greatly minimized.

It is further pointed out that the disk 10 may be made of a very thin gage metal and pressed 70 into the shape shown in the drawing. In such case, after the teeth are formed on the disk, the disk may be stamped by a die to form the wings. So, too, in such case, the slots 15 may not be necessary in the forming operation, and, therefore, 75

there will be no separate wing portions, but the inner marginal portion of the disk will be unbroken annularly and flared continuously around the central opening 11. Also, instead of each separate wing portion being curved or flared at only one corner, as herein first described, it may be flared throughout its entire width.

What I claim and desire to secure by Letters Patent, is:

- 10 1. A grinding plate including, a disk having a circular axial opening therethrough, pyramidal grinding teeth arranged on the working face of the disk in concentric rows, the disk being slotted on lines tangential to a concentric circular line within the axial opening and extending to a concentric circular line substantially at or near the middle of the disk body, the portions of the disk between the slots being offset from the plane of the disk body to provide an annular series of curved wings at the inner edge portion of the disk surrounding the axial opening.
- 15 2. A grinding plate including, a disk having a circular opening through the center thereof, separate grinding teeth on one face of the disk arranged in concentric rows and covering the entire surface of the disk, the disk being slotted
- 20 on lines tangential to a concentric circular line within the central opening of the disk and the portions of the disk between the slots being offset with curvature out of alignment with the plane of the rest of the disk from the side opposite to that on which said teeth are provided.
- 25 3. A grinding plate including, a disk having an axial circular opening therethrough, a group of concentric circular rows of teeth of a substantially constant size on the face of the disk and extending from the inner edge of the disk to an annular line near its outer margin, a second group of concentric circular rows of teeth of a substantially constant size extending from the annular line where the first group terminates to the peripheral edge of the disk, the teeth of the second group being smaller than the teeth of the first group, and an annular series of wings at the inner edge of the disk, said wings being separated on lines tangential to a circular line within the axial opening of the disk and each wing being offset with curvature out of alignment with the plane of the disk from the side of the disk opposite to that on which said groups of teeth are provided.
